No. 735,141.

PATENTED AUG. 4, 1903.

G. A. OGLE.
SURGICAL APPARATUS.
APPLICATION FILED DEG. 17, 1902.

NO MODEL.

UNITED STATES PATENT OFFICE.

GEORGE ATKIN OGLE, OF CATONSVILLE, MARYLAND.

SURGICAL APPARATUS.

SPECIFICATION forming part of Letters Patent No. 735,141, dated August 4, 1908.

Application filed December 17, 1902. Serial No. 135,543. (No model.)

To all whom it may concern:

Be it known that I, GEORGE ATKIN OGLE, a citizen of the United States, residing at Catonsville, in the county of Baltimore, State of Maryland, have invented certain new and useful Improvements in Surgical Apparatus, of which the following is a specification.

The present invention relates to improvements in medical apparatus, and has for its object to provide an apparatus adapted to utilize the action of centrifugal force to relieve the brain or other portions of the human body of excessive pressure from the blood.

The invention consists in the construction and arrangement of parts, that will be hereinafter described and claimed, and an embodiment thereof is illustrated in the accompanying drawings, in which—

Figure 1 is a perspective view of an apparatus constructed in accordance with the invention. Fig. 2 is a side elevation, partly in section, showing the mattress arranged at right angles to the position shown in Fig. 1. Fig. 3 is a detail perspective view of the rectangular support for the mattress-frame. Fig. 4 is a sectional view, on an enlarged scale, of the roller at the lower end of said rectangular support. Fig. 5 is a detail view of the connection between the rotating shaft and the mattress-frame support.

As stated above, the object of this invention is to utilize the action of centrifugal force to relieve the brain, for instance, of excessive pressure from the blood. To accomplish this, I provide means for supporting a mattress or support on which a patient can lie in such a manner that it can be rotated at any desired speed about an axis toward which the patient's head extends. This rotation will cause the blood to flow away from the brain and is found to be a very efficient agency for curing insomnia and other troubles due to the brain being subjected to too great a pressure.

The embodiment of the invention illustrated in the accompanying drawings includes a base consisting of a plate 1, which is mounted on suitable blocks 2, that are provided at their lower ends with outwardly-projecting flanges 3, which may be firmly secured to the floor of the room in which the apparatus is arranged. To said base is secured a frame or standard 4, in suitable bear-

ings on which is mounted a vertical shaft 5. The lower end of said shaft extends through the plate 1, and said lower end within the space between the blocks 2, the floor, and said plate 1 is provided with means by which said shaft can be connected with any suitable motor or source of power. As shown, a band-wheel or pulley 6 is secured to the shaft 5 for this purpose, and said wheel is provided with a pin or stud 7, by means of which, if desired, a driving-rod may be connected thereto to drive the shaft 5 instead of employing a belt.

The flange 3 may be formed separate from and secured by nails, bolts, or screws to the blocks 2, and said blocks need not be separated throughout the width of the base, but could be formed by a single piece having a slot of suitable dimensions extending through the periphery thereof to permit of the proper arrangement and action of the power devices.

The shaft 5 may be mounted in any suitable manner. Preferably the standard or supporting-frame 4 consists of at least three members, which are connected at the top by inwardly-extending arms 8 and near their lower ends by similar arms 9. The shaft 5 extends through apertures formed in the enlarged meeting ends of said arms 8 and 9 through an aperture in a boss 10 on the plate 1, suitable antifriction-balls 11 being provided wherever desired to cause the shaft to run as easily as possible.

At its upper end the shaft 5 is connected to a block or coupling-piece 12, which is provided with two laterally-projecting tubular members 13, into which are screwed the inner ends of rods 14. To the outer ends of the rods 14 are connected bars 15, the opposite ends of which are united by a cross bar or rod 16. The rods and bars 14 15 16 form a horizontal rectangular frame, which is mounted on and supported by the shaft 5 and by a guide-wheel 17, running on the base-plate 1. This guide-wheel, which is preferably grooved to engage and move freely around a circular track or guide 18 on the plate 1, is mounted in a hanger 19, depending from a casting, to which are connected inclined brace or stay rods 20 21, that are connected, respectively, to the cross-rods 16 and the rods 14. The upper ends of the rods 20 21 may be provided with suitable sleeves,

through which the rods 14 16 extend. As shown, the lower ends of the stay or brace rods 20 are connected directly to the casting in which the hanger 19 is supported, and the 5 lower ends of the other brace-rods 21 are sleeved on said rods 20 near the points of connection thereof with the casting.

The upper end of the spindle of hanger 19 preferably extends above the casting and is 10 secured in a plate or block 22, which fits closely between the brace or stay rods 20 21. The guide-wheel 17 is preferably mounted on a sleeve 23, through which the rod 24, connecting the side arms of the hanger 19, extends, and a series of antifriction-balls are fitted between said sleeve and suitable bearings on the rod 24.

The rectangular frame before referred to forms a support for a mattress-frame 25. 20 This frame is provided at one end with hooks 26, adapted to engage the rods 14 and connect said frame and rods when the mattress-frame is arranged in the position shown in Fig. 1. Similar hooks 27 are provided on one 25 or both of the side bars of the mattress-frame, so that said frame may be connected to the rods 14 when arranged at right angles to the position shown in Fig. 1, which may be desirable in certain cases. The hooks 26 or 30 27 prevent the mattress-frame from being thrown out of connection with the rods 14 and the shaft 5 by centrifugal force when the apparatus is in use.

Additional supports for the mattress-frame 35 are provided by means of chains 28. These are connected to the ends of the rods 14, which are preferably bent laterally and into hooks or eyes to which the chains are attached and after passing over suitable standards or uprights 29 are attached to the mattress-frame beyond the points where it is supported by the frame connected to wheel 17. The uprights or standards 29 may be formed integral with the side bars or rods 15 of the said 40 supporting-frame. Said uprights 29 may be connected by a cross-rod 30, fitted to move vertically on said uprights and provided at its middle with a short rod 31, that is adjustably connected to block 12 by an internally-threaded sleeve 32. By this means said head-bar 30 may be adjusted vertically, as desired.

The mattress-frame consists of a frame proper and a covering of woven wire, and when the apparatus is to be used the patient 55 lies upon an ordinary mattress or suitable blankets placed upon said mattress-frame.

The operation of the apparatus will be evident from the foregoing description and the drawings. The shaft 5 will be driven at any 60 desired speed, the rotation of the mattress-frame being varied according to the result it is desired to accomplish.

The mattress-frame is preferably in a substantially horizontal position, the outer end 65 being elevated slightly above the end adjacent the power-shaft. While the construction of mattress-frame herein shown and de-

scribed is preferred, because it is believed to be the most inexpensive and durable form now known, yet it is intended by the term 70 "mattress-frame" employed in the claims to include any other suitable support on which the patient to be treated can lie.

While, as stated in the preceding paragraph, the mattress-frame is generally supported in a substantially horizontal position, it may be desirable in some cases to arrange said frame at an angle, with the end adjacent the power-shaft highest. This is accomplished by engaging the proper set of hooks 80 on the mattress-frame with the cross-rod 30, which, as before described, is vertically adjustable, and thereby the said frame may be readily adjusted and retained at any desired inclination. 85

To positively prevent the hooks of the mattress-frame being disengaged from the connection with the power-shaft when the apparatus is in use, aligned apertures or passages 33 are formed in the members thereof, through 90 which suitable pins may be passed. Opposite sides of the rods 14 or 30 will thus be engaged by the curved sections of the hooks and the said pins and unintentional disengagement of the mattress-frame from the 95 power devices will be prevented.

As a means of indicating the effect produced by the apparatus a gage 34 may be attached to one of the rods 15. This consists of a short glass tube partially filled with a 100 suitable fluid, that may be colored, so as to be readily observed. When the apparatus is in use, the said liquid will be forced into one end of the glass tube, the extent of such movement from its normal level varying as 105 the speed of the shaft 5 is increased.

The apparatus above described may be advantageously used in treatment for rheumatism, congestions, and other disorders, where by properly changing the position of the patient the action of centrifugal force will send fresh blood to the desired part of the body, giving increased vitality and other incidental benefits. 110

Having thus described the invention, what 115 is claimed, and desired to be secured by Letters Patent, is—

1. In an apparatus for the purpose described, the combination of a vertical shaft, a mattress-frame connected with and extending radially from said shaft, and means for rotating said shaft and frame. 120

2. In an apparatus for the purpose described, the combination of a substantially horizontal mattress-frame mounted to rotate 125 about a vertical axis at one side thereof, and means for rotating the frame.

3. In an apparatus for the purpose described, the combination of a vertical shaft, a substantially horizontally arranged mattress-frame provided with hooks for engaging arms projecting laterally from said shaft, and means for rotating said shaft and the 130 mattress-frame engaged therewith.

4. In an apparatus for the purpose described, the combination of a vertical shaft, a substantially horizontally arranged mattress-frame adapted to be connected with said shaft, an auxiliary support for said mattress-frame, adapted to rotate about the axis of the shaft, and means for rotating the shaft. 5 of said rods, a wheel or roller engaging a circular guide on the base and connected to the frame formed by said arms, rods and cross-bar, a mattress-frame adapted to be supported on said frame and having hooks for engaging the arms on the vertical shaft, and means for rotating the shaft. 35
5. In an apparatus for the purpose described, the combination of a vertical shaft, 10 a substantially horizontal frame projecting radially from said shaft, an auxiliary support for the outer end of said frame, a mattress-frame adapted to be detachably secured to said shaft and frame, and means for rotating the shaft. 15
6. In an apparatus for the purpose described, the combination of a relatively stationary base, a vertical shaft supported on said base, a substantially horizontal mattress-frame adapted to be connected to said shaft, an auxiliary support for said mattress-frame including a wheel or roller engaging a circular guide on the base, and means for rotating the shaft. 20
7. In an apparatus for the purpose described, the combination of a relatively stationary base, a vertical shaft supported on said base and provided at its upper end with two oppositely-extending arms, rods connect- 25 ed to and extending outwardly from said arms, a cross-bar connecting the outer ends
8. An apparatus for the purpose described including a mattress frame or support mounted to rotate about a vertical axis at one side thereof. 40
9. In an apparatus for the purpose described, the combination of a mattress frame or support mounted to rotate about an axis 45 at one side thereof, and means for adjusting vertically the side of said frame adjacent said axis.
10. In an apparatus for the purpose described, the combination of a vertical shaft, 50 a mattress frame or support adapted to be connected to the upper end of said shaft, means for rotating the shaft, and means for adjusting vertically the connection between said frame and shaft. 55

In testimony whereof I affix my signature in presence of two witnesses.

GEORGE ATKIN OGLE.
